UNITED STATES PATENT OFFICE.

ALFRED J. GAIRING, OF JOHNSTOWN, PENNSYLVANIA, ASSIGNOR TO THE STEEL MOTOR COMPANY, OF SAME PLACE.

ELECTRIC TROLLEY DEVICE.

SPECIFICATION forming part of Letters Patent No. 612,410, dated October 18, 1898.

Application filed August 3, 1898. Serial No. 687,581. (No model.)

To all whom it may concern:

Be it known that I, ALFRED J. GAIRING, of Johnstown, in the county of Cambria and State of Pennsylvania, have invented a new and useful Improvement in Electric Trolley Devices, of which the following is a full, clear, and exact description, reference being had to the accompanying drawings, which form a part of this specification.

10 My invention relates to the class of electric trolley devices in which a grooved wheel or other contact device is carried by a pole secured on a car in such a way as to have universal movement, springs being provided to 15 press the contact device against the conductor.

The object of my invention is to provide a trolley device which has a minimum number of parts and which may be simply and cheaply 20 constructed, but which is durable in construction and effective in operation.

My invention consists, broadly, of a single torsion-spring secured at each end in a transverse position on the car, a trolley-arm being 25 secured about the central portion of said spring, so that both the lateral and vertical movements will be provided by the flexibility of the upward-pressure spring.

My invention further consists in the improved construction, arrangement, and combination of parts shown and described.

The annexed drawing is a perspective view of a trolley device embodying the features of my invention.

35 M is a suitable support.

C is a torsion-spring placed transversely on the support M.

E is a socket, in which the trolley-arm proper E, carrying the contact device G, is 40 secured.

The support M is a single casting comprising a base having two columns. The support is suitably fastened on the car. Vertical shanks g, which are formed at either 45 end of the spring C by the continuation of the coil, enter into recesses or sockets in the columns of support M. The spring C, after being placed on the support M, is rigidly secured by the clamps F F, bolted to the 50 columns.

The socket D is preferably constructed of two pieces of partly-curved metal bolted together about the central portion of spring C, so that when this spring is in its normal position the socket and arm will extend vertically. 55

The operation of my improved contact device is now clear.

I do not limit myself, however, to the specific construction of details, as many minor 60 changes may be resorted to without departing outside the scope of my invention.

What I claim, and desire to protect by Letters Patent, is—

1. The combination of a single transverse 65 torsion-spring secured at each end on the vehicle and a contact-carrying arm having its lower end secured about the central portion of the said spring.

2. In an electric trolley device, the combination of a support having columns, recesses or sockets in said columns, and a torsion-spring formed with vertical shanks at its extremities and means for retaining said shanks in said sockets. 70

3. The combination, in an electric trolley device, of a support having columns, a torsion-spring, means for securing the torsion-spring to said columns, a socket formed of two pieces of partly-curved metal clamped 80 together about said spring, and a contact-carrying trolley-arm carried by the socket. 75

4. The combination of the base or support having columns at each end, a socket in each column, a transverse torsion-spring having 85 vertical shanks entering said sockets, a pair of semicircular clamps engaging the ends of said spring and secured to the said columns, and a pair of semicircular members clamped about the central portion of said spring and 90 forming a socket for the trolley-arm.

In testimony whereof I have affixed my signature in presence of two witnesses.

ALFRED J. GAIRING.

Witnesses:

RICHARD EYRE,
H. W. SMITH.
